[57] CLAIM

The ornamental design of a massager, as shown and described.

DESCRIPTION

FIG. 1 is a perspective view of a massager, showing my new design;

FIG. 2 is a left side elevational view thereof, the right side elevational view being a mirror image thereto;

FIG. 3 is a front end elevational view thereof;

FIG. 4 is a rear end elevational view thereof;

FIG. 5 is a top plan view thereof;

FIG. 6 is a bottom plan view thereof; and,

FIG. 7 is a side elevational view thereof, with the broken line showing being for illustrative purposes only and forming no part of the claimed design.
